United States Patent Office

Des. 198,627
Patented July 14, 1964

198,627

AUTOMOBILE DESK

Earl F. Hamilton and Edwin K. Moore, Columbus, Ind., assignors to Hamilton Cosco, Inc., a corporation of Indiana

Filed June 26, 1963, Ser. No. 75,539

Term of patent 14 years

(Cl. D33—7)

FIG. 1 is a plan view of an automobile desk embodying our new design;

FIG. 2 is a side elevation thereof; and

FIG. 3 is an end elevation thereof.

We claim:

The ornamental design for an automobile desk, as shown.
